Primary Examiner—Cathron B. Brooks(74) *Attorney, Agent, or Firm*—Sand & Sebolt**CLAIM**

The ornamental design for a bottle security closure, as shown and described.

DESCRIPTION

FIG. 1 is a perspective view of a bottle security closure according to the concepts of the present invention; FIG. 2 is a front view of the bottle security closure of FIG. 1;

FIG. 3 is a right side elevational view of FIG. 2, the left side being a mirror image thereof;

FIG. 4 is a top plan view of FIG. 2;

FIG. 5 is a perspective view of a first alternative embodiment of the bottle security closure of the present invention; FIG. 6 is a front elevational view of the bottle security closure of FIG. 5;

FIG. 7 is a right side elevational view of FIG. 6, the left side being a mirror image thereof; and,

FIG. 8 is a top plan view of FIG. 6.

The broken lines are for illustrative purposes only and form no part of the claimed design.
